(57) **CLAIM**

We claim the ornamental design for a finger guard, as shown and described.

DESCRIPTION

FIG. 1 is a right-side elevational view of a finger guard, showing our new design;

FIG. 2 is a perspective view thereof;

FIG. 3 is a front elevational view thereof;

FIG. 4 is a rear elevational view thereof;

FIG. 5 is a right-side elevational view thereof, the left-side elevational view being a mirror image thereof;

FIG. 6 is a top plan view thereof; and,

FIG. 7 is a bottom plan view thereof.

The broken lines showing a person's hand in FIG. 1 depict environmental matter and form no part of the claimed design.
